MERCURY CONSERVING SWITCH

Joseph H. Staley, Columbus, Ind.

Application July 28, 1941, Serial No. 404,262

4 Claims. (Cl. 200—152)

This invention relates to mercury switches of the type formed by telescoping metallic members in which mercury is employed to complete a circuit between those metallic members upon suitable tilting or rocking of the switch. The immediate invention is particularly concerned with a switch of the above indicated nature for use to handle low voltages such as in the ordinary 6-8 voltage system employed in automobiles in the lighting and signaling circuits. Where a mercury switch is employed to handle currents of such low voltage, it is possible to employ a simplified structure as compared to the structure required for much higher voltages.

It is a primary object of this invention to provide an exceedingly simple structure which may be operated by use of far less mercury than has heretofore been employed in these types of switches, the conserving of the volume of mercury in each switch being of exceedingly great importance, particularly under war conditions existing at the present time.

A further important object of the invention resides in the peculiar structure developed to permit the use of the low mercury content and still preserve successful functioning of the switch. These and other important objects and advantages of the invention, such as the new and novel association of the various elements as set forth in the appended claims, will become apparent to those versed in the art in the following description of the invention as illustrated in the accompanying drawing, in which

Fig. 1 is a view in side elevation of a structure embodying the invention;

Fig. 2, a view in central vertical section, wherein the switch is shown in the closed circuit position;

Fig. 3, a view in similar section but inverted to be in an open circuit position in reference to the position shown in Fig. 2;

Fig. 4, a view in cap end elevation; and

Fig. 5, a view in central longitudinal section of a modified form of the invention.

Like characters of reference indicate like parts throughout the several views in the drawing.

Referring to the drawing, a metallic body 10 is formed to have a cylindrical bore 11 open at one end of the body and closed at the other end. As shown in Figs. 2 and 3, a cylindrical insulating sleeve 12 is telescoped over the body 10 from the open end thereof, and in the form herein shown, an end of this sleeve 12 is positioned in abutment with an annular shoulder 13 provided on the body 10.

The sleeve 12 thus positioned extends axially beyond the open end of the body 10. A metallic cap 14 is formed in the nature of a cup and is telescoped over the extending end of the sleeve 12 with a pressed fit, the sleeve 12 being of a resilient nature. The cap 14 is forced down over the sleeve 12 a suitable distance to leave an exposed length of the sleeve 12 between the body shoulder 13 and the rim of the cap 14 directed theretoward. The closed end of the cap 14 is at the same time spaced a distance from the open end of the body 10 so as to leave exposed therebetween the extending length of the sleeve 12. In the present form of the invention, the length of the sleeve 12 is proportioned in regard to the lengths of the body 10 and the cap 14 to properly position the cap 14 in relation to the body 10 when the end of the extended length of the sleeve 12 abuts the inside of the cap end.

The cap 14 is formed to have a central inwardly extending convex surface 15, herein shown as being formed by centrally pressing inwardly the end of the cap 14 to leave an externally exposed concave cavity 16. Such formation of the cap is produced readily by a stamping or die operation.

Before forcing the cap 14 into position over and around the insulating sleeve 12, as above indicated, a limited amount of mercury 17 is placed in the body 10. Referring to Fig. 2, in the absence of the central convex surface 15, this quantity of mercury 17 would have to be such that its top level would be above the end of the body 10 in order to be in contact both with the body 10 and the cap 14. For example, in a switch of the above description, where the internal diameter of the body 10 is .242 inch and the open end of the body 10 is spaced from the inside of the cap 14 a distance of .094 inch, and the internal diameter of the sleeve 12 is .287 inch, there would have to be employed at least two grams of mercury in the absence of the convex area 15. Now by forming that convex surface 15 wherein the depth of the cavity 16 is made to be .022 inch with a diameter of .156 inch (the thickness of the cap 14 being .022 inch), only one-fourth of that amount of mercury is required, namely one-half gram.

In this particular size of switch, the size being indicated as only one particular size and not in limitation of the invention, this small amount of mercury, due to its inherent nature, assumes a shape to one side of the axis of the switch as suggested in Fig. 2, the dimensions in any event of the various parts being such that when the

mercury tends to assume its inherent globular shape, it will roll to one side of the cap 14 by reason of the inwardly protruding surface 15, and in so doing will reach and be in substantial contact with the end of the body 10, when the switch is turned to have its axis substantially vertical, as shown in Fig. 2, with the cavity 16 on the under side. Then to break the circuit established by the mercury 17 between the body 10 and the cap 14, the switch is tilted back to a position which will cause the mercury 17 to flow down into the body 10, the extreme position in this direction of rocking being that shown in Fig. 3 where the switch has been rocked 180 degrees from the position shown in Fig. 2 and where the mercury 17 then rests on the closed end of the body 10.

Referring to the modified form of the invention as illustrated in Fig. 5 in the drawing, a body 18 is formed to receive telescopically therewithin by a forced fit an insulating sleeve 19. Over the other end of the sleeve 19 is forced a cap 20 to have its rim spaced from the rim of the body 18 to leave an exposed length of the sleeve 19 therebetween. The body 18 is provided with a central outwardly deformed part 21 to leave a concave well 22 on the inside thereof. The cap 20 is provided with a central pin 23 suitably fixed thereto to extend axially within the sleeve 19 to be directed toward and to terminate over this well 22. A globule of mercury 24 is provided so that when the switch in this form is rocked to have the body 18 undermost, this mercury 24 will flow into the well 22 and surround the lower end of the pin 23 and thereby complete a circuit through the pin 23 between the body 18 and the cap 20. It is therefore to be seen that in this modified form, a very small amount of mercury is employed for the purpose of bridging the two principal metallic members of the switch.

While not necessarily so, the insulating sleeve 12 and 19 in the two forms are employed to have their ends serve as positioning means for the respective metallic bodies and caps telescoping therewith, this feature serving to permit rapid and accurate production of the switches. The fits about the insulating sleeves in each instance are such that passage of gases inwardly or outwardly is to all practical purposes prevented. The exposed area of the insulating sleeve in either case within the switch is of no consequence since under the low voltages for which the switch is designed, there is no arcing that would unduly deteriorate the material. It is to be noted that in the form of the invention shown in Figs. 2 and 3, the cap 14 overlaps the body 10 through the intervening sleeve 12, thereby obtaining a greater structural strength than would be had in the form shown in Fig. 5 where there is simply an intervening length of the insulating sleeve 19 between the metallic members 18 and 20.

An important advantage of the structure shown in Fig. 5 is that the angle at which the switch is tipped to break the circuit (remove mercury 24 from pin 23) may be varied to meet predetermined conditions or construction of the switch tilting means. That is, by varying the diameter, the depth, or both of the well 22, or by varying the size of the mercury globule 24, the angle of tilt of the switch required to break the circuit may be predetermined to be a definite value, such as twenty degrees, thirty degrees, or forty-five degrees from the vertical.

While the invention has herein been shown and described in a more or less minute detail, it is ob-

vious that structural changes may be employed without departing from the spirit of the invention and I therefore do not desire to be limited to that precise form beyond the limitations as may be imposed by the following claims.

I claim:

1. In a mercury switch for low voltages, means for conserving the quantity of mercury required per switch comprising a pair of cupped metallic members; one of said members having a central inwardly protruding boss defining an annular channel therearound; a cylindrical, open end insulating sleeve; said cupped member having said boss being sealably engaged over an end of said sleeve, and the other cupped member being sealably engaged inside of the sleeve to extend toward the other member to leave an annular gap therebetween; and a quantity of mercury within the closed chamber formed by said cupped members with said sleeve, said mercury quantity being limited to be just sufficient to bridge said gap at one side of said boss when the switch is turned to have the boss-cupped member undermost.

2. In a mercury switch for low voltages, a metal cup; a second metal cup; a boss extending centrally inwardly from the floor of the second cup; a cylindrical insulating sleeve, both of said cups frictionally telescoping with said sleeve to have the cups form end closures on said sleeve and to have a cylindrical wall of the first cup extending inside of said sleeve to approach the other cup but to terminate without contact therewith, whereby a cylindrical chamber is formed with metal closures at each end and with a metal wall approximating its length; and a limited quantity of mercury in said chamber, said quantity being limited to that size of an inherently forming globule about one side of said boss when the switch is tilted to have the second cup undermost, the spacing between nearest parts of said cups within said chamber being such as to have said globule bridge thereacross in said tilted position.

3. In a mercury switch for low voltages, a metal cup; a second metal cup; a boss extending centrally inwardly from the floor of the second cup; a cylindrical insulating sleeve, both of said cups frictionally telescoping with said sleeve to have the cups form end closures on said sleeve and to have a cylindrical wall of the first cup extending inside of said sleeve to approach the other cup but to terminate without contact therewith, whereby a cylindrical chamber is formed with metal closures at each end and with a metal wall approximating its length; and a limited quantity of mercury in said chamber, said quantity being limited to that size of an inherently forming globule about the side of said boss when the switch is tilted to have the second cup undermost, the spacing between nearest parts of said cups within said chamber being such as to have said globule bridge thereacross in said tilted position, a shoulder on said one cup against which said sleeve abuts, said second cup abutting by its end the other end of said sleeve, whereby the difference in lengths of said sleeve and of said first cup wall determines the gap width between the cups.

4. In a mercury switch for low voltages, a metal cup; a second metal cup; a boss extending centrally inwardly from the floor of the second cup; a cylindrical insulating sleeve, both of said cups frictionally telescoping with said sleeve to have the cups form end closures on said sleeve

and to have a cylindrical wall of the first cup extending inside of said sleeve to approach the other cup but to terminate without contact therewith, whereby a cylindrical chamber is formed with metal closures at each end and with a metal wall approximating its length; and a limited quantity of mercury in said chamber; the clear-

5 ance between said cups within said chamber, and the diameter and height of said boss being correlated so that said mercury quantity may be one-fourth that otherwise required in the absence of said boss.

JOSEPH H. STALEY.
